UNITED STATES PATENT OFFICE.

WILLIAM E. SHORE, OF NEW YORK, N. Y.

VACUUM-PUMP FOR PLAYER-PIANOS.

1,356,496.

Specification of Letters Patent. Patented Oct. 19, 1920.

Application filed October 19, 1917. Serial No. 197,424.

To all whom it may concern:

Be it known that I, WILLIAM E. SHORE, a subject of the King of Great Britain and resident of the city of New York, State of New York, in the United States of America, have invented certain new and useful Improvements in Vacuum-Pumps for Player-Pianos, described in the following specification, and illustrated in the accompanying drawings, that form part of the same.

The principal objects of the invention are to devise a power driven pump which will be extremely efficient and silent in operation and will automatically adjust itself to produce a uniform vacuum and regulate the load upon the motor.

A further important object is to devise a construction in which the driving motor will be thoroughly ventilated and kept cool and which will eliminate the danger of fire.

The principal features of the invention consist in the novel construction and arrangement whereby the motor and driving 25 cranks are contained in a rigid unitary structure which is flexibly supported within the bellows casing and whereby an elastic compensating means is interposed in the operating connections of the motor and bellows.

A further important feature consists in the novel manner of silencing the air discharge by first expanding the air in an expansion chamber and then dissipating it 35 through a multiplicity of openings in the inclosing casing.

In the drawings Figure 1 is a vertical elevation view in part section through the bellows casing and one of the bellows.

40 Fig. 2 is a vertical elevational section through the silencer and bellows casing showing the motor and bellows driving connections in elevation and in part section through the gear housing.

45 Fig. 3 is a vertical sectional detail showing the worm drive and bearing support for the motor shaft.

Fig. 4 is a vertical section through the motor shaft.

50 Fig. 5 is a sectional detail of a modified form of bellows connecting rod.

Upon reference to the drawings it will be seen that the electric motor 1 is suspended centrally from the top of the bellows casing 2 by flexible tubular members 3 and that the motor shaft is vertically arranged.

A tubular member 4 provided with a flange 5 at the upper end is secured to the motor casing and encircles the shaft, a bearing sleeve 6 being arranged at the upper end. 60 The lower end of the member 4 is formed with a flange 7 to which the gear housing 8 is rigidly secured and laterally extending arms 9 are formed thereon with perpendicularly arranged sleeve members 10 which 65 slidably encircle the tubular rods 11 rigidly secured in the top and bottom of the bellows casing 2.

Buffers 12 and 13 of resilient material are arranged at the top of the motor case and 70 the bottom of the gear housing 8.

The lower end of the motor shaft extends into the gear housing and is stepped in the ball bearing 14. The housing 8 is a closed 75 casing and is filled with lubricating oil. The motor shaft 15 is bored through the center and is filled with wicking 16 which carries oil upwardly to the sleeve bearing 6, lateral ducts 17 being bored in the shaft to carry the oil outwardly. The surplus oil is 80 returned to the well in the gear housing through the tubular member 4.

The housing 8 is formed with transversely arranged bearings 18 in which the crank shaft 19 is journaled and secured to 85 the shaft 19 within the housing is the worm wheel 20 which meshes with the worm 21 secured to the motor shaft.

The cranks 22 and 23 on the outer ends of the crank shaft are preferably arranged in 90 right angular relation to each other and to these are connected the bellows operating connecting rods 24.

The pair of bellows 25 are arranged at the side of the casing 2 farthest from the 95 crank shaft 19 and the operating members 26 are provided with brackets 27, which brackets are formed with upper and lower pairs of lugs 28 and 29.

The outer ends 30 of the connecting rods 100 24 are pivotally connected between the upper pairs of lugs 28 and grease cups 31 are arranged at both ends of the rods to supply lubricant to the bearing. This arrangement of the crank shaft connections provides a 105 long free movement in the connecting rods.

A second pair of bellows 32 are arranged at the opposite side of the casing 2 and these are provided with brackets 33 having paired 110 lugs 34 which correspond with the lower lugs 29 of the opposite bellows 25.

Blocks 35 are pivotally secured in the

paired lugs 29 and 34 and these are rigidly connected to the opposite ends of the spiral springs 36 which thus form flexible connections between the opposing bellows on opposite sides of the casing.

It will be understood from this description that the rotation of the motor shaft and worm gearing operates the crank shaft and the motion of the cranks operates the bellows 10 25 and as the cranks at each end of the crank shaft are arranged in right angular arrangement the bellows 25 will be operated so that there will be a continuous suction in the vacuum duct which is connected with 15 the intake of each. The opposing bellows 32 are operated in opposition to the bellows 25 and as the connection between them is effected by the spring connectors 36 there will be an equalizing cushioning effect.

20 In Fig. 5 I have shown a modified form of connector which may be used in place of the members 36. In this form the blocks 35 are replaced by the rods 35' and 35''. The rod 35' is of tubular form and the rod 35'' 25 is telescoped into it and forms an air cushion and the pins *a* and *b* are connected to the spring 36'.

Either of these forms of connectors have a compensating effect in the operation of the 30 bellows. The tension of the springs is such that in opening the bellows the springs relieve according to the vacuum pull and this elastic connection equalizes the vacuum and prevents overloading the motor.

35 The casing 2 is formed with a channel 37 in the top wall which extends down the sides and communicates with the intake openings 38 in the bellows and a suction tube 39 which leads to the vacuum chest of 40 the piano player is connected to the top of the casing and opens into the channel 37.

The air from the bellows is discharged into the interior of the casing 2 and provides a continuous flow of air around the 45 motor which has the effect of preventing overheating.

The bellows casing 2 is arranged within an outer casing 40 being supported on a false bottom 41 spaced from the main bottom 42 and which is perforated with a plurality of holes 43. The casings 2 and 40 are preferably formed of non-combustible material and the interior of the casing 40 is lined with a suitable sound deadening material 44.

50 The air is discharged from the interior of the casing 2 into a duct 45 which discharges into the expansion chamber 46 between the bottoms 41 and 42 and from this chamber 60 it escapes through the multiplicity of holes in the bottom 42. This arrangement provides a very effective silencer which eliminates all sound from the discharge.

The casing 40 may be arranged within the 65 piano and the discharge carried by a suit-

able tube beyond the piano case or it may be in the form of a separate cabinet if desired.

The construction herein described has been devised to provide the smoothest possible operation. The motor and crank shaft driving mechanism are a rigid unit and this unit is carried on a flexible suspension which with the arrangement of the rigid vertical guides 11 eliminates all vibration. The connections between the crank shaft and bellows are flexible and jar and vibration in this part is obviated and the whole is then inclosed in a sound proof casing and forms a very compact unit.

80 What I claim as my invention is:—

1. A vacuum pump for player pianos, comprising, a closed casing having a discharge opening, bellows arranged within said casing and at opposite sides and connected with a vacuum intake and discharging into the casing, a motor resiliently suspended within said casing between said oppositely arranged bellows, a crank shaft transversely journaled in bearings rigidly supported from the motor casing, connecting rods operating on said crank shaft and connected to said bellows, and rigid vertical guides supporting said motor and crank shaft against the thrust of the connecting rods.

85 2. A vacuum pump for player pianos comprising a closed casing having a discharge opening, bellows arranged at opposite sides of said casing and connected with a vacuum intake and discharging into the casing, a motor supported between said bellows, connecting rods operatively connecting said motor with the bellows on one side of said casing, and elastic members connecting the directly operated bellows with the opposing bellows and forming the sole means of operating the latter.

90 3. A vacuum pump for player pianos comprising a closed casing having a discharge opening, bellows arranged within said casing and arranged in opposing pairs and connected with a vacuum intake and discharging into the casing, a motor supported between said bellows, means operatively connecting said motor with the bellows on one side of said casing, and coil spring members connecting the directly operated bellows with the opposing bellows and forming the sole means of operating the latter.

95 4. A vacuum pump for player pianos comprising a closed casing, bellows arranged within said casing, an electric motor flexibly suspended from the top of said casing and having its shaft vertically arranged, a sleeve member secured to the motor casing and loosely encircling the motor shaft and having a sleeve bearing at the upper end for said shaft, a closed gear casing 100

- rigidly secured to said sleeve member and having a bearing support for the lower end of the motor shaft, said motor shaft having an oil duct extending upwardly from 5 the bottom and directing the oil to the sleeve bearing, a crank shaft extending transversely of said gear casing, a gear wheel mounted on said crank shaft within said gear casing and operated from the motor 10 shaft, and means connected to the outer ends of said crank shaft for operating the bellows.
5. A vacuum pump for player pianos comprising a closed casing, bellows arranged within said casing and connected with the vacuum intake and discharging into the casing, a motor supported within said casing and operating said bellows, an outer sound proof casing inclosing the aforesaid 15 20 casing and having a double bottom forming an expansion chamber having a plurality of discharge holes leading therefrom, and a discharge duct leading from the inner casing to said expansion chamber.
- 25 6. A vacuum pump for player pianos, comprising, in combination, a casing, a motor suspended from the top of said casing, a crank shaft horizontally journaled and supported from the motor casing and having a crank at each end said cranks being arranged in right angular relation the one to the other, a pair of bellows arranged at one side of said casing, connecting rods arranged on said cranks and connected one with each of said bellows, a pair of bellows 30 arranged at the opposite side of said casing, and means operatively connecting the oppositely arranged pairs of bellows.
7. In a vacuum pump for player pianos the combination with a casing and bellows arranged in said casing, of a motor frame secured to the top of the casing, a tubular member secured to the motor frame having a bearing sleeve at the top end, an armature shaft journaled in said sleeve and extending downwardly through said tubular member, a gear casing secured to the bottom of said sleeve and forming an oil well, a stop bearing in said gear casing supporting said shaft, means for feeding oil from 35 40 45 said oil well to the sleeve bearing, a crank shaft geared to said motor shaft, and means connecting said crank shaft with said bellows.

WM. E. SHORE.
